ADJUSTABLE STRETCHER FRAME

William A. Davis, Chicago, Ill.

Application March 11, 1936, Serial No. 68,317

4 Claims. (Cl. 45—24)

This invention relates to a stretcher frame. The construction herein described is particularly adapted for holding a piece of cloth in position for embroidery work and other needle craft, but the invention may be adapted as well to other uses.

An object of the invention is to provide an adjustable stretcher frame which will support a cloth on all sides in the same plane, thus eliminating wrinkles and curvature over the surface of the cloth. Another object is to provide an adjustable stretcher frame which will permit the cloth to be fastened at points on a side of the frame and which will yet permit stretching of the cloth between the points at which it is fastened.

In common constructions of adjustable frames two members are adjustably secured on top of two other members. Obviously, the tops of two members are in a plane different from that of the tops of the other two, and when the cloth is attached to the tops of all members wrinkles and unevenness result. Also, as the cloth when pulled taut has a tendency to assume a single plane, it is likely to be pulled loose at points where it is fastened to the under members. These and other objections are overcome by the construction herein disclosed. Further objects and advantages of my invention will become apparent as the specification proceeds.

Figure 1 is a plan view of an embodiment of the invention with the structure completely assembled and showing a fragment of cloth to illustrate how the cloth may be attached; Figure 2 a sectional view as seen from line 2 of Figure 1; Figure 3 a view in elevation of a cross member omitting the blocks; Figure 4 a plan view of a cross member with the blocks omitted; Figure 5 a plan view of a side member; Figure 6 a view in elevation of a side member; and Figure 7 a view in perspective of one of the blocks.

In the illustration given, A denotes the side members, and B denotes the cross members. A' and A² are left and right side members respectively, and B' and B² are top and bottom cross members respectively.

The construction of side members A is more clearly shown in Figures 5 and 6 of the drawings. These members may consist simply of wood strips having slots 10 and 11. Slots 10 and 11 may be extended toward each other or entirely joined as one long slot, but the preferred construction is shown with a middle unslotted portion mainly because this lends greater strength and will per-

mit sufficient adjustment of the frame for practical purposes.

The cross members B may consist of wooden cross strips 12 as clearly illustrated in Figures 3 and 4, and slidable wooden blocks 14 more clearly shown in Figure 7. The cross strips 12 are centrally slotted throughout their length except for the middle portion 13. Middle portion 13 is raised above the main level of the strip and its thickness exceeds that of the slotted portions 10 of the strip by the thickness of the side members A.

The blocks 14, which may be made of wood, have slotted sides and have I-shaped cross sections. The thickness of the upper portion 15, 15 above the slot, is the same as that of the side members A, the slots 16 and 17 are of such size as to admit an edge of cross strip 12, and the center portion 18 is of such width as to be conveniently received within slots 19 or 20 of the cross strips 12. Thus, the blocks 14 may be slidably mounted on the cross strips, the center portion 18 of the blocks sliding in slots 19 and 20 of the cross strips, and the edges of the cross strips sliding in slots 16 and 17 of the block. Strips 12 may be adapted to receive any desired number of blocks of suitable lengths.

After the blocks have been slidably mounted upon the cross strips, fillers 21 are inserted in the ends of the slots 19 and 20 and secured by cross pins 22. However, sufficient space is left for the sliding of the blocks so that the blocks may be moved endwise to allow side members A to be placed between them, and preferably there should be left additional sliding space as shown in Figures 1 and 2. If desired the raised portion 13 of members B may be omitted and this part of the strip slotted to accommodate slidable blocks just as are the end portions.

Side members A are fastened to cross members B by bolts 23 extending through the slots of each member and tightened by wing nuts 24 on the under side of the frame. The side members may be placed with their edges abutting the ends of middle portion 13 of the cross members, as member A² is shown in Figures 1 and 2; or, if a larger frame is desired, one or more blocks on members B may be pushed inwardly until they abut against portion 13, and side members A then fastened with their edges abutting the outer ends of these blocks, as member A' is shown in Figures 1 and 2.

The cloth 25 or other material which is to be stretched for embroidery work or other purposes may be attached to each of the side and cross

members by any suitable means such as by the use of thumb tacks 26. In the illustration given the cloth is shown attached near the outer edges of the side members, but it may be attached near 5 the inner edges as well.

In the use of this stretching frame the side members are first attached to the cross members at such an adjustment as most nearly accommodates the size of the cloth to be mounted.

10 Adjustment of the distance between cross members B is made by sliding bolts 23 in slots 10 and 11; this adjustment is limited only by the length of these slots. Adjustment of the distance between side members A is made as previously explained by inserting one or more blocks between the side members as they are mounted; this adjustment is limited to intervals corresponding to the length of the blocks. However, 15 adjustment may be made for cloth of various widths by selecting the number of blocks which most nearly gives the desired spacing and then attaching the cloth either at the outer edge or the inner edge of the side members as happens to be convenient.

20 After the cloth is attached at all sides, the frame may again be adjusted for stretching the cloth taut. This is done by loosening wing nuts 24 and moving one or both side members A outwardly to take up some of the additional space left between the slideable blocks, the bolts 23 being allowed to slide along slots 19 and 20 until the cloth is drawn sufficiently taut, and again tightening nuts 24 to secure the members in attachment. After the cloth has been used for 25 some time in this position it has a tendency to stretch and again become loose. To remedy this the frame may be adjusted as before, or, if all additional space is taken up, it may be necessary to slide added blocks between the side members.

30 The edges of the cloth or material may be 40 tacked to the blocks within the side members as well as to central portions 13. In this construction, when the side members are moved apart to stretch the cloth, the blocks within the side members to which the cloth is attached will also slide outwardly. This allows stretching of the cloth between points of attachment at the edges.

35 The tops of the middle portions 13, the tops of blocks 14, and the tops of side members A, are all of an even level. This causes cloth having 45 its edges attached to the tops of these various members to be suspended at points in one plane only. Such a mounting is highly desirable in that it eliminates much wrinkling and unevenness in the cloth.

40 55 In the form of the invention herein described only the cross members are equipped with slideable blocks, but it should be understood that the side members may also be equipped in a similar fashion. Also numerous other changes may be 60 made in the construction without departing from the spirit of the invention. The foregoing detailed description has been given for clearness of understanding only, and no unnecessary limi-

tations should be understood therefrom, but the appended claims should be construed as broadly as permissible, in view of the prior art.

I claim:

1. An adjustable stretcher frame comprising: 5 a pair of spaced cross members each including a strip provided with a raised middle portion and slotted end portions, said members being equipped with slideable blocks mounted on said end portions, the tops of said blocks being at 10 an even level with said middle portions; and a pair of slotted side members attached to said strips by bolts extending through the slots of said strips and side members, said bolts being slideable along the slots of said side members to 15 vary the spacing between said cross members, and being slideable in the slots of said strips to vary the spacing between said side members.

2. An adjustable stretcher frame comprising: 20 a pair of spaced cross members each including a strip provided with a raised middle portion and slotted end portions, said members being equipped with slideable blocks mounted on said end portions, the tops of said blocks being at an even level with the said middle portions; and a pair 25 of slotted side members attached to said strips by bolts extending through the slots of said strips and side members, said bolts being slideable along the slots of said side members to vary the spacing between said cross members, and being slideable in the slots of said strips to vary the spacing between said side members; said side members being adapted to be attached to said strips at either end of any of said slideable blocks.

3. An adjustable stretcher frame comprising: 30 a pair of spaced cross members each including a strip provided with a raised middle portion and slotted end portions, said members being equipped with slideable blocks of different lengths mounted on said end portions; and a pair of 40 slotted side members attached to said strips by bolts extending through the slots of said strips and side members, said bolts being slideable along the slots of said side members to vary the spacing between said cross members, and being slideable in the slots of said strips adjacent the ends 45 of said slideable blocks to vary the spacing between said side members; said side members being adapted to be attached to said strips at either end of any of said slideable blocks, and said side 50 and cross members having their top surfaces within the points of attachment aligned at an even level.

4. An adjustable stretcher frame comprising: 55 cross members having unslotted central and end portions and longitudinal slots extending between said central portion and said end portions, slideable blocks extending through said slots and having their bottom sides below said cross members, and side members transversely attached to 60 said cross members, the tops of said side members being flush with the tops of said blocks.

WILLIAM A. DAVIS.
